J. W. Lobb, Inventor

UNITED STATES PATENT OFFICE.

JUSTUS WARNER LOBB, OF DES MOINES, IOWA.

SPINNING-TOP.

SPECIFICATION forming part of Letters Patent No. 660,161, dated October 23, 1900.

Application filed December 21, 1899. Serial No. 741,163. (No model.)

To all whom it may concern:

Be it known that I, JUSTUS WARNER LOBB, a citizen of the United States, residing at Des Moines, in the county of Polk and State of Iowa, have invented a new and useful Spinning-Top, of which the following is a specification.

This invention relates to spinning-tops, and more particularly to that class which are spun by winding a cord about them and then throwing them violently, the object of the invention being to provide a structure which is particularly adapted for plugging. By the term "plugging" is meant that game in which the top is thrown at another top with the intent of striking it and possibly splitting it. This game has a tendency to split the top that is being spun at the objective top, due to the driving of the plug up into the body of the top. The present invention produces a structure in which the plug is held firmly in place and in which the body is strengthened by the form and arrangement of the plug.

In the drawings forming a part of this specification, and in which similar numerals of reference designate like and corresponding parts in both views, Figure 1 is a perspective view showing a top constructed in accordance with the present invention. Fig. 2 is a central longitudinal section of the body of the top, the plug being shown in elevation.

Referring now to the drawings, the top comprises a body portion 5, having the usual exterior shape and provided with the usual cord-notches upon the lower portion of its surface.

Centrally and longitudinally of the body portion 5 is formed a passage 7, the lower portion of which is tapered downwardly to a slight extent, as shown at 8, while the upper portion for substantially half the length of the passage has a constant diameter, upon the surface of which are screw-threads 9.

Through the passage 7 is passed a plug having a lower downwardly-tapering portion 10, corresponding to and adapted to closely fit the tapered lower portion 8 of the passage, the extremity of the plug projecting from the lower end of the passage below what is known as the "point" of the top, this projecting extremity having a cord-groove 11 just below the lower extremity of the body

portion, the plug below this groove being formed cylindrical, as shown at 12, and terminating in a cone 13, forming the plug proper. The upper portion of the plug is cylindrical and is screw-threaded, as shown at 14, these threads engaging the threads 9 and acting to hold the plug against longitudinal displacement. The upper end of the plug is provided with a head 14^a, which rests against the head of the top-body and acts to further strengthen the top. This head 14^a has a peripheral groove 15, which receives the spinning-cord in the usual manner.

It will be seen that with the above construction the taper of the plug is such as to permit the plug to be snugly fitted into the body portion of the top and at the same time to prevent splitting of the body portion, due to the wedging of the plug into the passage. Moreover, the plug increases the weight of the top and makes the structure rigid to facilitate plugging.

What is claimed is—

1. A top comprising a body portion having an axial passage therethrough, threads in the passage, and a plug passed entirely through the passage and having threads engaged with the threads in the passage, said plug having a head engaging the upper end of the body and said plug projecting at its opposite end from the lower end of the body, whereby the material of the central portion of the upper end of the top will be protected to prevent splitting when struck by another top.

2. A top comprising a body portion having a passage therethrough, a portion of which is tapered downwardly and the remaining portion of which is threaded, and a plug having a tapered portion and a threaded portion adapted to engage the corresponding portions of the body, said plug having a head to lie against the head of the body.

3. A top comprising a body portion having a passage therethrough, the upper portion of which is threaded and the lower portion unthreaded, and a plug lying in the passage and extending therefrom, said plug having a threaded portion and an unthreaded portion engaging the corresponding portions of the passage.

4. A plug comprising a body portion having a passage therethrough, the lower portion

of which passage is tapered downwardly and the upper portion of which passage is provided with threads, and a plug lying in the passage and extending therefrom, said plug
5 having a tapered portion fitting the tapered portion of the passage and having threads engaging the threads of the passage.

In testimony that I claim the foregoing as my own I have hereto affixed my signature in the presence of two witnesses.

JUSTUS WARNER LOBB.
